Primary Examiner — Deanna L Fluegeman*(74) Attorney, Agent, or Firm* — Banner & Witcoff, Ltd.(57) **CLAIM**

The ornamental design for a display screen with icon, as shown and described.

DESCRIPTION

The single FIGURE is a front view of a display screen showing my new design.

The broken line showings of the head of the runner and the display screen are for environmental purposes only and form no part of the claimed design.
